EDWIN T. GREENFIELD, OF KIAMESHA, AND JOHAN GUSTAF V. LANG, OF NEW YORK,
N. Y., ASSIGNEES TO GREENFIELD PAPER BOTTLE COMPANY, OF NEW YORK, N. Y.,
A CORPORATION OF NEW JERSEY.

APPARATUS FOR CONTRACTING RINGS.

1,384,752.

Specification of Letters Patent.

Patented July 19, 1921.

Application filed September 28, 1915. Serial No. 53,086.

To all whom it may concern:

Be it known that we, EDWIN T. GREENFIELD and JOHAN GUSTAF V. LANG, citizens of the United States, and residents, respectively, of Kiamesha, county of Sullivan, State of New York, and of the borough of Manhattan, city of New York, county and State of New York, have made certain new and useful Inventions Relating to Apparatus for Contracting Rings, of which the following is a specification.

The invention relates to an apparatus which is particularly adapted for the manufacture of paper bottles.

In the manufacture of paper receptacles it is desirable to fixedly secure in place upon the paper receptacle as it is being made a clamping ring which is U-shape in cross section. In actual practice, this ring is preferably made so that one leg of the U is longer than the other whereby the paper can be clamped between the legs when they are forced toward each other in a manner to cause a natural bend or set in the paper.

The apparatus which is shown in the drawings is particularly adapted for use in securing a bottom member in place in the body member of a bottle by means of a clamping ring of the class just referred to and which ring is pressed in such a manner as to maintain a liquid-tight joint between a flange on the bottom and the body member of the bottle which are clamped or secured together by the ring.

As showing a specific embodiment of the invention reference is made to the drawings forming a part of this specification, in which drawings,

Figure 1 is a vertical sectional view of the press. In this figure the ring which is to be operated upon is also shown. This figure is a view taken along the line 1-1 of Fig. 4.

Fig. 2 is a partial vertical sectional view of the press. In this figure the bottom portion of the bottle is shown and the parts are shown in the position which they occupy at the time when the ring to be operated upon is about to be engaged by the member which compresses the ring.

Fig. 3 is another partial vertical sectional view of the press. In this figure the parts

are shown in the position which they occupy at the end of the pressing operation.

Fig. 4 is a plan view, partially broken away, of the press. This figure is drawn on 55 a smaller scale than Figs. 1 to 3.

Figs. 5 and 6 are, respectively, plan and vertical sectional views of the expandible and contractible spring-ring which is utilized in the press.

Fig. 7 is a vertical side view, partially broken away, of an assembled bottle body and bottom prior to the bottom clamping ring being placed upon it.

Fig. 8 is a vertical side view, partially 65 broken away, showing the clamping ring which is utilized to secure the bottom of the bottle to the body portion of the bottle.

Fig. 9 is a vertical view, partially broken away, of the lower portion of the bottle. 70 This view shows a clamping ring after it has been compressed so as to securely clamp the bottom and body portion of the bottle together in a manner to make a liquid-tight joint.

The press comprises any suitable frame member as 1 to which there is secured in a suitable manner an anvil or resisting member 2. This anvil member is positioned on the frame by means of a projecting portion 80 4 which enters a socket 5 and screws 6 are provided to secure the anvil in place. An expandible and contractible ring 7 surrounds the anvil. This ring is of a springy material and is in the form of a spiral; it is 85 supported by a series of hammers or pressing members 8 that surround the ring. These hammers are carried by or mounted upon the frame 1 as by depending portions 9 which enter an annular socket portion 10 90 of the frame. These hammers are mounted so that they, or at least their upper ends, can move inwardly and outwardly in a radial direction, their inward movement being accomplished through the medium of a ring 95 or sleeve 11 which surrounds them. This sleeve 11 has a portion 12 which engages cam portions 13 that are located on the outer sides of the hammers, and from an inspection of the drawings it is manifest that when 100 the sleeve 11 is forced upwardly the hammers 8 will be forced inwardly by the en-

gagement of the portion 12 on the sleeve with the cams 13 on the hammers. The upward movement of the sleeve 11 is accomplished through the medium of a lever 14 which is fulcrumed on the frame at 15 and which engages pins 16 that are on the sleeve 11.

The press is also provided with means for properly positioning the work-piece relative to the anvil and hammers and in the apparatus as shown this means is provided as a part of the hammers which projects under the anvil and is indicated by the reference character 17. The expandible and contractible ring 7 is preferably made of spring steel and takes the form of a series of coils so that the spring will entirely surround the anvil at all points. This spring has an internal extending projection or shoulder 18. The upper ends of each of the hammers or pressing members extend inwardly and downwardly so as to serve as a guiding means whereby the work will be readily placed in position in the machine. It will be noted that the lower ends of these guiding means extend inwardly beyond the inner edge of the top portion of the expandible and contractible ring 7.

The press is constructed so that a solid or continuous ring M which is U-shape in cross section (see Fig. 8) can be placed in the press in the manner shown in Fig. 1. The assembled bottle body member and bottom are then placed in the machine, as shown in Fig. 2, in a position so that the lower edges of the bottle body and the depending flange of the bottom will enter the cavitary portion of the ring. The lever 14 is then operated so that the hammers and expandible and contractible ring will be caused to assume the position shown in Fig. 3. In other words, as the parts are forced to the position shown in Fig. 3 it will be observed that the hammers or pressing members have been moved inwardly in a manner to cause the ring 7 to contract and as the ring contracts the individual coils in it have a slight sliding movement relative to each other and also relative to the ring being pressed, thus tending to iron out any crimps which form in the outer leg of the ring M. It will thus be noted that the spiral ring 7 performs the pressing and forming operation and hence may be referred to as a pressing or a forming ring.

It will furthermore be noted that the shoulder 18 of the ring is arranged relative to the free edge of the short inner leg X so that the shoulder will engage only that portion of the outer leg Y which extends beyond or above the free end of the shorter leg. The anvil 2 serves as a resisting member to support the shorter or inner leg while the upper end of the outer leg is being forced toward the anvil. When the press-

ing operation has been completed the upper end of the inner leg has been forced toward the anvil a sufficient distance to cause the depending flange at the bottom and the lower edge of the bottle body to be clamped between the legs of the ring and in a manner to cause a natural bend or set to be imparted at 19 to the parts that are thus clamped.

The improvements herein set forth are not limited to the precise construction and arrangement shown and described as they may be embodied in many forms and modifications without departing from the spirit and scope of the invention.

What is claimed is:

1. A press comprising an anvil, a contractible spiral pressing ring surrounding the anvil, a series of pressing members arranged about said ring, and means for forcing said pressing members toward said anvil into engagement with the ring so as to contract the same, said pressing members having a portion that projects under said anvil.

2. A press comprising an anvil, a contractible spiral pressing ring surrounding the anvil, a series of pressing members arranged about said ring, and means for forcing said pressing members toward said anvil into engagement with the ring so as to contract the same.

3. A press of the class described comprising in combination an anvil, a continuous pressing ring of spiral form surrounding said anvil, which ring is capable of being contracted, a series of pressing members arranged about said ring, and means for forcing the pressing members toward the anvil and inwardly against said ring, said ring also having an inwardly extending shoulder.

4. A press of the class described comprising in combination an anvil, a continuous pressing ring of spiral form surrounding said anvil, which ring is capable of being contracted, a series of pressing members arranged about said ring, and means for forcing the pressing members toward the anvil and inwardly against said ring.

5. A press of the class described comprising in combination an anvil portion, a contractible spiral pressing ring extending around said anvil portion and arranged to engage a work-piece when the latter is in operative position relative to the anvil, a series of pressing members engaging the outer portion of said ring, and means for forcing the pressing members toward the anvil, the press also being provided with means for positioning a work-piece relative to the anvil while being pressed.

6. A press of the class described comprising in combination an anvil portion, a contractible spiral pressing ring extending around said anvil portion and arranged to engage a work-piece when the latter is in

operative position relative to the anvil, a series of pressing members engaging the outer portion of said ring, and means for forcing the pressing members toward the anvil.

7. A press having a resisting member which is provided with a vertically extending anvil face on its periphery, an expansible and contractible ring surrounding said anvil face, said ring being of spiral formation and having at its upper portion an inwardly projecting shoulder, a series of pressing members which surround and engage said ring, and means for forcing said pressing members inwardly so that they will cause a contraction of the ring, the pressing members each having an inwardly projecting portion which extends below the ring and which serves as means for positioning the work-piece as the latter is being pressed.

8. A press having a resisting member which is provided with a vertically extending anvil face on its periphery, an expansible and contractible ring surrounding said anvil face, said ring being of spiral formation and having at its upper portion an inwardly projecting shoulder, a series of pressing members which surround and engage said ring, and means for forcing said pressing members inwardly so that they will cause a contraction of the ring.

9. A press having a resisting member or anvil against which a work-piece is pressed when being operated upon, a ring of spring spiral formation surrounding said anvil and arranged to engage and press the work-piece when in operative position relative to the anvil, a series of pressing members, and means for forcing said pressing members against said ring so as to contract the latter.

10. A press of the class described comprising in combination a fixed anvil surrounded by an expansible and contractible forming ring, movable pressing members which engage the outer portion of said ring, and means for forcing said pressing members inwardly.

11. A press of the class described comprising in combination a frame, an anvil mounted on said frame, a series of pressing members carried by said frame, an expansible and contractible spiral forming ring surrounding said anvil and carried by said pressing members, and means for forcing the pressing members inwardly to cause a contraction of said ring.

12. A press of the class described comprising in combination a frame, a continuous anvil carried by said frame, an expansible and contractible forming ring surrounding said anvil, pressing members surrounding and engaging said ring, which pressing members have on their exterior portion cams, an outer ring surrounding and engaging the cam portions of said pressing members, and a lever mounted upon the frame for operating said outer ring, the construction of the cam portions of the pressing members and the outer ring being such that as the latter is moved along the cams it will force the pressing members inwardly and thus contract the expansible and contractible ring.

13. A press of the class described comprising in combination an anvil, an expansible and contractible spring-ring surrounding said anvil and arranged to engage a work-piece when the latter is in operative position relative to the angle, a series of pressing members engaging said spring-ring, and means for forcing the pressing members inwardly, the expansible ring being of sufficient strength to force the pressing members outwardly when allowed to do so.

14. A press of the class described comprising in combination a frame supporting an anvil, an expansible and contractible spiral forming ring surrounding said anvil, a series of hammers carried by said frame and supporting said ring, and means for forcing the hammers inwardly.

15. A press of the class described comprising in combination an anvil, a spiral pressing ring in the form of a spring-ring surrounding said anvil, a series of hammers surrounding said ring, and means for forcing the hammers inwardly so as to cause the ring to contract, the hammers having at the upper portion thereof downwardly and inwardly inclined portions which serve to guide a work-piece into the space where it can be operated upon, the lower ends of said downwardly and inwardly inclined portions also being arranged so as to project inwardly beyond the inner portion of said ring.

This specification signed and witnessed this 21st day of September, A. D., 1915.
